Inventor:

Omer Bisson

By Percy H. Moore,
Attorney.

UNITED STATES PATENT OFFICE.

OMER BISSON, OF CALLAWAY, MINNESOTA.

SAW-SET.

1,348,622.

Specification of Letters Patent. Patented Aug. 3, 1920.

Application filed May 3, 1919. Serial No. 294,509.

To all whom it may concern:

Be it known that I, OMER BISSON, citizen of the United States of America, residing at Callaway, in the county of Becker and State 5 of Minnesota, have invented certain new and useful Improvements in Saw-Sets, of which the following is a specification.

This invention relates to improvements in saw-sets more especially designed for circular or cross-cut saws, while it is equally adapted for use in setting the teeth of all kinds of saws, including the common buck-saw etc.

The invention has for its object to provide for readily, quickly and effectively setting the saw-teeth, also to provide for the holding of the saw blade firmly as against casual, accidental or shifting movement when performing the filing or sharpening 10 operation; also to regulate the tooth setting operation.

With these objects in view, together with others which will appear as the invention is more fully disclosed, by the following 15 description and accompanying illustration, the nature thereof consists of certain instrumentalities and features of construction substantially as hereinafter fully described and specifically pointed out by the appended 20 claims.

In the accompanying drawings is illustrated the preferred embodiment of my invention and wherein it will be understood that various changes and modifications as 25 relate to the detailed construction and arrangement of the parts may be made without departing from the spirit or scope of the claims, and in which drawings:

Figure 1 is a front elevational view of 30 my improved saw-set;

Fig. 2 is a central sectional elevation thereof on a line through the saw-tooth clamping or setting elements and the guiding stud of one of these and its receiving 35 slot.

Fig. 3 is an end view looking in the direction of the arrow Fig. 1.

In carrying out my invention, I provide a holder or member 1, in practical use being 40 preferably in the form of a frame and wooden, said frame or holder being adapted to receive a mandrel or shaft 2 which extends clear through said holder. Said holder has at one end a ledge or flange 3 projecting therefrom at its forward edge, and formed within said end and said ledge

is an approximately V or Y shaped recess or depression 4 for the reception of the saw-blade tooth to be operated upon or set.

The mandrel or shaft 2, which is preferably cylindrical in transverse section, has integral with one end thereof a laterally projecting head or projection 5, positioned to extend beyond the ledge-equipped end of said mandrel or shaft and adapted to co-operate with a flat or stub-ended screw for effecting the saw-tooth setting operation again referred to, said screw being threaded to work in the ledge 3 and be projected therebeyond. The projected end of the 60 screw is thus adapted to be opposed to the projection of the mandrel head as shown in Figs. 1 and 3 whereby with the saw-tooth disposed upon said stubbed end of said screw, the projecting portion of the head 5 of 65 the mandrel or shaft 2 may be suitably brought forcibly down upon the tooth, as in effecting the requisite deflecting or operation of the saw-tooth, presently more fully disclosed. The stub-ended screw 6 is received below the ledge or flange 3 of the holder or member 1, in a longitudinal groove or recess 7 formed in said holder or member for the guidance of said screw 6, said groove or recess being in continuation of the threaded 70 passage in the ledge or flange 3 receiving said screw. For guidance of the mandrel or shaft 2 rectilinearly and against turning in said holder 1, the mandrel or shaft is provided with a lateral stud 8 received within a longitudinal slot 9 formed in said holder. By suitably adjusting the stub-ended screw the amount of set or deflection 75 of the saw-tooth may be readily varied or regulated as is apparent, this being readily effected by applying suitable means as a wrench or pincers to the outer end of the screw and suitably actuating the same.

The mandrel or shaft 2 is equipped or encircled by a preferably helical spring 10 80 with one end resting upon a shoulder 11 of said mandrel and its opposite end resting upon an annular shoulder 12 upon the wall of the bore or interior surface of the holder or member 1, said spring serving to automatically expel or project the mandrel or shaft from the latter as the handle or crank 13 is reversely revolved upon said mandrel.

The hand or crank 13 has a freely turning screw connection with the mandrel or shaft 110 3, exteriorly of the holder 1, whereby, upon turning the crank or handle to the right,

the mandrel or shaft is drawn inwardly bringing its head or projection 5 down, with effective action, upon the saw-tooth as called for in effecting the setting operation as previously herein set forth and at the same time compressing and putting the spring 10 under tension for the purpose as above described.

It is thought that from the foregoing description of the construction, arrangement and combination of parts, my invention will be readily understood for its effective application and use.

I claim:

15 A device of the type described, including a holder having a laterally projecting flange, a stub-ended screw, a guiding recess or groove for said screw, and a crank-equipped mandrel received within said

holder, and having a laterally projecting head coöperating with said screw for engaging an interposed object, one end of said holder and said lateral flange thereof having formed therein a continuous depression of approximately Y outline, receiving the projected end of said screw and said mandrel head, said holder having a longitudinal slot opening through one end thereof and said mandrel having a lateral stud received and guided by said slot to retain said mandrel against turning.

In testimony whereof I affix my signature in presence of two witnesses.

OMER BISSON.

Witnesses:

ESTHER ALSON,
LOUIS W. VASALY.
